UNITED STATES PATENT OFFICE.

JOHN H. B. SHANNON, OF NEWARK, NEW JERSEY, ASSIGNOR TO DISINFECTANT AND UTILITIES CORPORATION, A CORPORATION OF NEW YORK.

AUTOMATIC SPRAYING DEVICE.

1,122,544.

Specification of Letters Patent.

Patented Dec. 29, 1914.

Application filed February 24, 1914. Serial No. 820,463.

To all whom it may concern:

Be it known that I, JOHN H. B. SHANNON, a citizen of the United States, and a resident of Newark, in the county of Essex and State of New Jersey, have invented certain new and useful Improvements in Automatic Spraying Devices, of which the following is a specification.

My invention relates to automatic sprayers for disinfecting the atmosphere of halls, theaters, etc.

In public halls and theaters where a number of people are gathered for any considerable time, the air, besides becoming vitiated, may become contaminated by germs and bacilli. This has long been recognized as a danger and attempts have heretofore been made to disinfect halls of this character by means of a hand spraying device, which is usually operated by an attendant during intermissions. Devices of this character are unsatisfactory because the disinfecting effect soon disappears, and in some cases the use of these hand sprayers is positively dangerous on account of the fact that the spraying takes place in close proximity to the spectators.

The main object of this invention is to produce a compact and efficient device for maintaining a hall disinfected at all times.

One feature of the invention resides in an atomizer operated by a reciprocating pump, together with an outlet from the pump to the atomizer, and an intake for the pump which is of insufficient capacity to supply the capacity of the pump, thereby causing a back suction through the outlet from the pump. Owing to the small capacity of this intake and by means of the arrangement of the tank, nozzles and sleeve device the disinfecting liquid is conserved for use to the maximum measure of time through being very finely atomized, thereby getting a maximum amount of efficiency from a determined amount of disinfecting liquid. Another feature of the invention lies in the construction and arrangement of the sleeve device with the atomizer spraying device whereby poorly atomized liquid is retained within the sleeve device, and by the arrangement of the said sleeve device, the tank and the nozzles, is collected back into the liquid tank to be properly atomized at a future time, thus conserving the liquid.

Other features of construction, combina-

tion of parts, and arrangement of elements will appear as the specification proceeds.

In the accompanying drawings the invention is embodied in a concrete and preferred form, but changes of construction may be made without departing from the legitimate and intended scope of the invention as expressed in the appended claims.

In the said drawings: Figure 1 is a view of a device embodying the invention, in elevation, and partly in section. Fig. 2 is a view looking in the direction of the arrow in Fig. 1, partly in section. Fig. 3 is a top plan view, and Fig. 4 is a detail view of the motor support.

Similar characters of reference refer to similar parts throughout the specification and claims.

To a base member 1 is attached a liquid container or tank 2 having an offset portion 3 therein, said tank containing near the offset portion thereof the atomizer 4. There is a vent 5 near the atomizer, with a cap covering the same, for the purpose of filling said tank. Within the offset portion 3 of said tank is placed the cylinder 6 of the pump, having a reciprocating piston 7 operating therein. Running through the piston 7 is an air intake 8, having a check controlling device 9 to check the passage of air outward from said cylinder 6 after it has once entered. A pipe or air supply device 10 supplies air from the cylinder and is connected to the atomizing device.

The air intake 8 being of a size insufficient to supply air equal to the capacity of the pump, upon the suction stroke of the piston 7, a somewhat slight suction is had, thereby forming a partial vacuum within the cylinder 6, which vacuum, in turn, causes a "sucking-in" effect at the spraying device, and by reason of the parts herein-after described, the disinfecting liquid is conserved.

The intake 8 must not be of too insufficient capacity, as the total amount of air required could not be fed through the supply device 10 but would choke therein and thereby cause an undue and unnecessary load on the motor, owing to the constricted mouth of the supply device 10.

To the atomizing device 4 are attached pressure and spray tubes 12 and 13 of relatively small size, each ending in a close vicinity to each other, the tube 12 being con-

nected to the part 10 and the tube 13 leading from the tank 2.

Surrounding the two tubes 12 and 13 is a sleeve liquid retaining device 12' of a size sufficient to leave considerable space between the inner wall thereof and the outer walls of the tubes 12 and 13. This device 12' sets upon a disk 12'' having apertures 13' and 13'' respectively cut therethrough and opening into the liquid tank. By this arrangement, any liquid which is poorly atomized, and therefore being heavier than the thoroughly atomized liquid, will collect upon the inner wall or be confined within the device 12'. When the "sucking-in" effect is had, as heretofore described, this poorly atomized and comparatively heavier liquid will be sucked back into the lower part of the device 12' and will then fall by gravity back into the tank 2 through the apertures 13' and 13''. By this arrangement, the disinfecting liquid is conserved to the maximum efficiency of result. Spanning the liquid tank 2 are two arched members 14 and 15 respectively, said arched members having inturned portions 16 which lie under said liquid tank 2 and are attached to said base member 1 by means of screws, bolts, rivets or other suitable fastening means, fastened through suitable apertures 17 in said inturned portions 16. Connecting these two arched members 14 and 15 are a pair of bridge members 18 and 19 respectively, having near their centers suitable apertures 20 for the mounting of a rotary motor 21 thereupon, said motor being fastened by bolts 22 or other suitable fastening devices. On an end of the shaft 23 of the motor is mounted a worm 24 to mesh with a suitable reducing worm gear 25. To said reducing worm gear 25 is attached a crank disk 26 having an aperture 27 therein for the adjustable coupling therewith of a suitable piston pitman 28, said pitman having a multiplicity of apertures 29 therein for adjustable coupling with said crank disk 26. The other end of the pitman 28 is connected to the piston 7 of the pump at 30 by means of any suitable coupling device. These devices are inclosed in a suitable casing 31 which is attached to the base 1 by means of screws 32 or other suitable fastening devices. Upon the top of this casing 31 is attached a snap switch 33 of the ordinary construction, the circuit wires 34 thereof running to the motor for suitable manipulation, said snap switch controlling the current received through proper wires 35 which are run through an aperture 36 in the casing and up through the said casing again to the switch.

The casing 31 is perforated in the upper part of the two end portions as indicated at 37 and 38 respectively, and the major part 65 of these perforations are in alinement with

the play of the fan 39 attached in any suitable or desired manner to the rotor shaft 23 at the opposite end from the worm gear 24, that is, at the rear of the motor 21. This fan 39 forces air in through the casing at 70 one end and out at the other past the end of the nozzle 12' thereby assisting to atomize and diffuse a certain amount of the disinfecting liquid that would otherwise collect at the mouth of the retaining device in the 75 form of a light mist.

In operation the snap switch 33 is closed, which, starting the motor, operates the crank disk 26 at a reduced speed through the medium of said worm and worm gear reducing devices. To this crank disk is attached the piston pitman, adjusting it according to the structure of the particular device in which it is mounted. By this arrangement the piston is operated in a reciprocatory fashion in said cylinder, drawing air through the intake and air supply device upon the upward stroke of the piston 7, while upon the down stroke of the piston 7 the intake check valve 9 is closed, allowing no air to escape by this means, but allowing the air in the cylinder 6 to pass to the atomizer, where the liquid is sprayed forth.

What is claimed, is:

1. An automatic atomizing device comprising adjacent liquid and air nozzles, a tank connected to said liquid nozzle, a liquid collecting device surrounding said nozzles and in communication with the tank, a reciprocating pump, an unobstructed connection between said pump and air nozzle whereby the flow of air on the compression stroke of the pump sets up spraying action and whereby flow of air on the suction stroke feeds back the surplus liquid in the collecting device, and an intake for the pump having a valve adapted to be closed on the compression stroke, said intake being of a size insufficient to supply an amount of air to the pump equal to the capacity of the pump.

2. An automatic atomizing device comprising liquid and air nozzles adjacent to each other, a tank connected to said liquid nozzle, a collecting sleeve surrounding said nozzles to retain poorly vaporized liquid and return same to said tank, a reciprocating pump, an unobstructed supply device between said pump and air nozzle to supply air to said nozzle to spray the liquid and to cause the retained liquid in said surrounding device to feed back into said tank upon the suction stroke of said pump, and an intake to said pump of a size insufficient to supply an amount of air to the pump equal to the capacity of the pump whereby a certain amount of air is drawn into the pump on its suction stroke through the collecting sleeve, air nozzle and supply device.

3. An automatic atomizing device comprising a reciprocating pump, a restricted

air supply device to said pump, two adjacent tubes, one to supply air and one to supply liquid to be sprayed by the air received through said air supplying tube, a tank connected to and supplying liquid to said liquid tube, a device surrounding said tubes and feeding into said tank to retain superfluous liquid, and means connecting said air supplying tube to said pump to either feed air to said tube to spray liquid or to suck superfluous liquid so that it will flow back into said tank from said surrounding device upon the reciprocation of said pump.

4. An automatic spraying device comprising a tank, a liquid nozzle feeding from said tank, a superfluous liquid retainer feeding into said tank, an air supply tube running within said retainer and adjacent to said liquid nozzle to atomize the liquid, a reciprocating pump connected to said air supply tube, and a restricted air inlet to said pump to restrict the full feeding of air to the pump to cause a back suction through the air supply tube and thereby cause the super-

fluous liquid in the retainer to flow back into the tank.

5. An automatic spraying device comprising an atomizer having tubular nozzles and a superfluous liquid retainer, a liquid tank having said nozzles in communication therewith, and a reciprocating pump connected to one of said tubular nozzles and having a restricted intake closed on the compression stroke so that upon the compression stroke of the pump air is supplied to said tubular nozzle to spray liquid supplied through the other of said tubular nozzles and upon the suction stroke the superfluous liquid is fed back to the tank from the retainer through the action of one of said nozzles.

Signed at New York city in the county of New York and State of New York this 17th day of February A. D. 1914.

JOHN H. B. SHANNON.
